OUTDOOR WEATHERPROOF MARKER

Donald E. Haslam, Skellytown, Tex.

Application July 12, 1937, Serial No. 153,252

2 Claims. (Cl. 40—10)

This invention relates to markers especially adapted for oil and gas wells and has for the primary object the provision of an efficient and inexpensive device of this character which may be readily set up at a selected place and has means for the accommodation of an information and identification card, giving necessary data relating to a well, the device being so constructed as to protect the card from weather elements and which may be seen for a maximum distance so it may be easily located and will permit a person to easily inspect the card and data thereon with the least amount of inconvenience to the person making the inspection.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a front elevation, partly in section, illustrating a marker constructed in accordance with my invention and showing the cover of the device elevated to expose to view the identification card denoting desirable data relating to a well.

Figure 2 is a fragmentary transverse sectional view illustrating the device.

Figure 3 is a fragmentary front elevation illustrating the cover of the device in a closed position.

Figure 4 is a sectional view taken on the line 4—4 of Figure 2.

Referring in detail to the drawing, the numeral 1 indicates a base having integral therewith a sleeve 2 for the reception of the upper end of a supporting post 3. A set screw 4 is carried by the sleeve and may be turned against the post for anchoring the base on the post. The post may be of any desired construction, preferably made of metal, and is driven or otherwise inserted into the ground at a selected place, for instance, adjacent an oil or gas well. A vertically arranged card supporting plate 5 is formed on the base 1 and includes marginal flanges 6. Vertically arranged guides 7 are formed on the

plate and have certain faces thereof in parallelism with the side edges of the plate. A detachable clip 8 is provided on the plate and cooperates with lugs 9 formed on the base in removably supporting a transparent panel and identification card 11 which may bear any data suitable to give information relative to the well adjacent which the device is located.

A cover 11' is slidably mounted on the guides 7 and plate 5 and may be lowered into engagement with the base so as to completely conceal and protect the identification card against weather elements. The lower end of the cover is shaped to fit over the base. Said cover is provided with a set screw 12 which may be turned in engagement with the plate 5 for securing the cover in a lowered position. Upon the outer face of the cover may be placed certain indicia for the purpose of giving information. The parts of this device, except the transparent panel and identification card, are preferably constructed of some suitable metal so as to resist weather elements and have a prolonged life.

What is claimed is:

1. A marker including an identification card, a base, a supporting means for said base, a vertically arranged plate formed on said base and including marginal flanges, means for removably mounting the identification card on said plate, and a cover enclosing the plate and identification card to protect the card from weather elements and adapted to be elevated to expose the card.

2. A marker including an identification card on a transparent panel, a base, a supporting means for said base, a card supporting plate formed on said base, guides carried by said plate, means for removably mounting the identification card and the transparent panel on said plate, and a cover slidable on said guides and plate and normally resting on the base and shaped to conform thereto and capable of being slid relative to the plate to expose the identification card, and a set screw carried by the cover to engage with the plate for preventing displacement of the cover.

DONALD E. HASLAM.
